RAILWAY BRAKE BEAM STRUCTURE

Herbert W. Ekholm, Chicago, Ill., assignor to Chicago Railway Equipment Company, Chicago, Ill., a corporation of Illinois

Application December 26, 1947, Serial No. 793,814

8 Claims. (Cl. 188—223.6)

1

The invention relates to railway brake beams of the truss type in which compression and tension members converge near the ends of the beam and mount end structures for carrying brake shoes and for engaging hangers to support the beam from the truck framing.

One object of the invention is to assemble the beam members to one another by an integral enlargement on each end of the tension member and without weakening the tension and compression members as by threading, drilling or the like.

Another object is to mount the brake head so the brake head may pivot relative to the tension rod when side pressure is applied to the head at any angle.

Another object is to facilitate assembly and disassembly of the beam by providing an end structure including a removable element which normally holds the tension member to the compression member.

Another object is to form the seat, for receiving a supporting hanger, and the center lug, for receiving a brake shoe, in the end structure removable element which may be made of hardened steel and thereby constitute a removable wear plate.

Another object is to assemble a reversible brake head to either end of a beam of the kind described.

These and other detail objects as will appear below are attained by the structure illustrated in the accompanying drawings, in which:

Figure 1 is a plan view of a truss type brake beam embodying the invention.

Figure 2 is a horizontal section through the left-hand end of the beam approximately on line 2—2 of Figure 3.

Figure 3 is an end view of the beam.

Figure 4 is a transverse vertical section through the right-hand ends of the compression and tension members and taken approximately on line 4—4 of Figure 1.

Figure 5 is a detail showing a modification of the end structure removable element.

Figures 6 and 7 are views similar to Figures 3 and 4, respectively, and show another form of the invention.

The beam shown in Figures 1—4 includes a compression member 1 of channel-shaped cross section, a round rod tension member 2 and a strut 3 intermediate the ends of the beam. The end portions of the compression and tension members converge, each end portion of the tension member being received between the compression

2

member flanges 1a and extending beyond the ends of the compression member. The end portions of the tension member are upset or otherwise enlarged as indicated at 4.

5 A brake head 5 is mounted on each end of the beam and has forwardly projecting lugs 6 receiving a lug S' of a brake shoe S. A passage 7 in brake head 5 receives the end portions of the tension and compression members. The back wall 10 of passage 7 engages the outer face of the compression member web 1b and the top and bottom walls 9 of the passage engage the outer faces of compression member flanges 1a. The brake head seats the end of the compression member at 13 and seats the enlargement 4 on tension member 2 at 14. An arcuate web 10 extends vertically across passage 7 from its top wall to its bottom wall and the rear face of web 10 engages the forward edges of flanges 1a. The forward concaved face of web 10 receives tension member 2. Passage 7 opens forwardly of the beam to facilitate assembly of tension member 2 to head 5.

A removable block 11, preferably of hardened steel, is received in the passage opening and between top and bottom walls 9. The rear face 11a of block 11 is concaved and opposes the forward concaved face of web 10 and cooperates therewith to form a sleeve fitting around the tension member. Vertically disposed rivets 12 extend 20 through passage top and bottom walls 9 and through block 11 and secure the block to the head. The forward face of block 11 is recessed at 13a to receive a hanger 13b to support the beam from the truck frame. Forwardly extending fingers 35 11b on block 11 are seated against lugs 6 and are disposed to engage the shoe lug to support the shoe and resist its vertical movement. By making block 11 of wear resisting material, and by providing for its removal if worn, the life of the 40 brake head is prolonged.

The brake beam may be assembled readily with blocks 11 removed from the heads by inserting the end portions of the compression member into brake head passages 7 behind webs 10 as described above. Each end portion of the tension member is moved perpendicularly of its length through the associated passage opening into engagement with web 10 and the block 11 is secured in the passage by rivets 12 to close the passage opening and to cooperate with enlargements 4 on the tension member to maintain assembly of the beam. Enlargements 4 may be any desired shape but the portion seated on the brake head preferably is rounded as indicated so the brake head may pivot relative to the tension rod when

side pressure is applied at any angle to the brake head.

The brake head structure shown in Figure 5 is similar to that described above except that wear elements 11b are not provided between the projecting lugs as described above. Instead, the forward face 20a of block 20 abuts rearwardly projecting ledges on lugs 6a.

The beam shown in Figures 6 and 7 comprises a compression member 31 and a tension member 32 having their end portions converging and received in a passage 33 in an end member 34. A vertically disposed arcuate web 35 extends vertically across the passage and confines the end portion of the compression member in the rear portion of the passage. The forward concaved face of web 35 receives tension member 32. A brake head 36 is attached to the forward faces of lugs 38 on end member 34 by rivets 39. A concaved rear face 36a of brake head 36 opposes the concaved forward face of web 35 and secures tension member 32 therebetween. The end of tension member 32 is enlarged at 37 to maintain assembly of the beam members.

The brake head is of the duplex type and may be used interchangeably on either end of the beam. The forward portion of the brake head has an integral continuous hanger seat 41 and is stronger than non-reversible heads having a horizontal rivet extending through the hanger seat for securing the beam member.

The brake beam may be assembled by inserting the end portion of the compression member in end member passage 33 and seating the end portion of tension member 32 in the concave face of web 35. Brake head 36 then is riveted to end member 34 and secures tension member 32 therebetween.

The details of construction may be varied substantially without departing from the spirit of the invention, and the exclusive use of those modifications coming within the scope of the claims is contemplated.

What is claimed is:

1. In a railway truss type brake beam, a compression member and a tension member with their end portions converging, there being an integral enlargement on each tension member end portion, structure at each end of the beam having a passage receiving the associated end portions and having an opening facing transversely of the beam, said structure opposing the end of said compression member to restrain movement of said structure inwardly of the beam and opposing said enlargement to restrain movement of said structure outwardly of the beam, said structure including a separate element fitting in said opening and against said tension member end portion and restraining relative movement of said members transversely of the beam and forming a seat for a brake shoe and maintaining assembly of said structure and said members.

2. In a railway truss type brake beam, a compression member and a tension member with their end portions converging, structure at each end of the beam having a passage receiving the associated end portions, said structure including an integral arcuate web extending into said passage and spaced from the front and back of the passage, said compression member end portion being confined in said passage at one side of said web and said tension member end portion being received in said passage at the other side of said web, a removable element opposing said web, said tension member being confined between said element and

said web, and an enlargement on said tension member end portion to prevent withdrawal of said tension member from said structure.

3. In a railway truss type brake beam, a compression member and a tension member with their end portions converging, a brake head at the end of the beam having a passage to receive the associated end portions, an element received in said passage and confining said tension member end portion, and an integral enlargement on said tension member end portion opposing said head and preventing withdrawal of said tension member end portion from said passage and thereby maintaining assembly of said brake head to said members, said element being of relatively hard metal and including a recess for receiving a beam hanger and also including a bearing for supporting a brake shoe lug.

4. End structure for a railway brake beam including lugs for mounting a brake shoe and having a passage adapted to receive the converging end portions of a tension and a compression member, an integral web extending into said passage and adapted to confine the compression member end portion and to receive the tension member end portion, and a detachable element restricting said passage and opposing said web, said tension member being confined between said element and said web.

5. End structure for a railway brake beam including lugs for mounting a brake shoe and having a passage extending transversely through the structure and having an opening facing longitudinally of the beam and adapted to receive the converging end portions of a tension and a compression member, an integral arcuate web extending across said passage opening and adapted to confine the compression member end portion at one side and to receive the tension member end portion at the other side, and a detachable element closing said passage opening and opposing said web, said tension member being confined between said element and said web.

6. A brake head for a railway brake beam comprising elements for mounting a brake shoe, a passage extending transversely through the brake head and having an opening facing longitudinally of the beam and adapted to receive the converging end portions of a tension and a compression member, and a separate block restricting said passage opening and adapted to oppose the tension member end portion and maintain assembly of the brake head and the members, said block including a seat for a brake beam hanger and a wear surface for supporting a brake shoe lug.

7. In a railway truss type brake beam, a compression member and a tension member with their end portions converging, an integral enlargement on each tension member end portion, structure at each end of the beam supporting said enlargement and provided with a passage having an opening forwardly of the beam, the structure having a rear part mounted on the compression member and including an integral arcuate web extending into the passage, said compression member end portion being confined in said passage at one side of said web and said tension member end portion being received in said passage through said opening to assemble the beam and being positioned at the other side of said web, and said structure including a separable element across said opening opposing said web, said tension member being confined between said element and said web.

8. A brake beam as described in claim 7 in which the separable element comprises a brake head secured to the structure rear part.
